UNITED STATES PATENT OFFICE.

FRANK H. PATRICK, OF GANDY, LOUISIANA.

DESIGN FOR AN ARTICLE OF MANUFACTURE.

53,206.

Specification for Design.

Patented Apr. 15, 1919.

Application filed August 28, 1918. Serial No. 251,850. Term of patent 7 years.

To all whom it may concern:

Be it known that I, FRANK H. PATRICK, a citizen of the United States, residing at Gandy, in the parish of Sabine and State of Louisiana, have invented a new, original, and ornamental Design for an Article of Manufacture, of which the following is a specification, reference being had to the accompanying drawing, forming part thereof.

The figure is a front elevational view of an emblem, an article of manufacture, showing my new design.

I claim:—

The ornamental design for an article of manufacture as shown.

FRANK H. PATRICK.

Witnesses:

J. E. WAGLEY,
M. V. LEACH.
